UNITED STATES PATENT OFFICE.

LESTER ERNEST MILKEY, OF SANDUSKY, OHIO.

PAPER-MAKING MACHINE.

1,387,061.

Specification of Letters Patent. Patented Aug. 9, 1921.

Application filed August 6, 1920. Serial No. 401,725.

To all whom it may concern:

Be it known that I, LESTER E. MILKEY, a citizen of the United States, and a resident of Sandusky, in the county of Erie and State of Ohio, have invented a new and Improved 5 Paper-Making Machine, of which the following is a full, clear, and exact description.

This invention relates to improvements in 10 paper making machines, an object of the invention being to provide improved means for removing the moisture from the paper, fabric, or other similar material while the latter is moving in the form of a sheet.

15 A further object is to provide an improved blow roll against which paper, fabric, etc., is smoothly held between perforated aprons, strips or conveyers so that air of any desired temperature can be forced through or 20 into contact with the sheet to remove the moisture therefrom.

25 A further object is to provide a machine of the character stated in which air under pressure is utilized for removing the moisture from the paper and which may also be utilized as a conveyer for chemicals for disinfecting, or liquids for coloring the sheet.

30 A further object is to provide a machine of the character stated in which a high operating speed is possible by simply increasing the air pressure as the sheet however soft or tender cannot break because it is confined between a pair of perforated belts or endless carriers.

35 With these and other objects in view the invention consists in certain novel features of construction, and combinations and arrangements of parts as will be more fully hereinafter described and pointed out in the 40 claims.

In the accompanying drawings—

Figure 1 is a view in longitudinal section illustrating my improved paper making machine.

45 Fig. 2 is a view in transverse section through the blow roll.

Fig. 3 is an enlarged fragmentary view in section of the periphery of the blow roll.

50 Fig. 4 is a view in longitudinal section illustrating a modification.

Fig. 5 is a fragmentary view in section of a modified form of blow roll.

1 represents a sheet of paper, fabric, or other material as it is formed by any approved method in the manufacture of paper.

and the like, and 2 are the ordinary suction boxes over which the sheet 1 is fed.

3 represents my improved blow roll which is of general cylindrical form having heads 4 and 5 in its ends fixed or secured to a hollow hub 6. The head 4 has a tapering or conical central portion 7 with a cylindrical extension 8 in which a cylindrical valve 9 is mounted and a coiled spring 10 is located around the valve 9 and between a disk 11 on the outer end of the extension 8 and a shoulder 12 on the valve exerting inward pressure on the valve to maintain the conical or tapering inner end 13 of the valve in airtight engagement with the conical or tapering portion 7 of head 4.

The roll 3 is divided by radial partitions 14 into a circular series of radial compartments 15 and each of these compartments has an inlet 16 which is adapted to register with ports 17 in the valve 9 so that certain of the chambers or compartments 15 are in communication with the air inlet valve 9 and receive air therefrom while the other chambers are cut off from the air supply. 80 An air supply pipe 17' communicates with one end of the valve 9 and supplies air under the desired temperature for the purpose intended.

It will be noted particularly by reference 85 to Fig. 2, that only the chambers 15 at the lower portion of the roll are in communication with the air inlet and it is these lower chambers which serve to direct the air against the sheet 1 as will more fully herein-after appear.

The roll 3, or rather the cylindrical wall of said roll, is provided with perforations 18 extending through the wall thereof and the extreme outer periphery or surface of 95 the roll is made with flared outlet mouths 19 communicating with the perforations 18 so that the outer surface of the roll presents as far as possible an extended air discharging surface to direct the air against the sheet 1. 100

20 represents a perforated belt or apron which is preferably of wire mesh and is passed around three rollers 21, 22 and 23 with the upper run of the belt 20 located around the under portion of the blow roll 3. 105

24 represents a second endless perforated belt or apron which is also preferably of wire mesh and this belt or apron 24 is passed around rollers 25 and 26 and is located directly against the periphery of the roll 3. 110

The sheet 1 passes between the endless belts or aprons 20 and 24 and is carried thereby around the lower portion of the periphery of the blow roll so that in its passage around the blow roll it is supported between a pair of perforated belts or aprons and the air under pressure escaping from the chambers 15 can blow through or against the paper without injuring the same because the paper is effectually supported by the pair of perforated belts or aprons between which it is inclosed. A drip pan 26 is located below the blow roll 3 so as to catch any moisture which may be discharged from the paper. While I have shown the apron 20 as an independent apron, it may constitute a portion of the ordinary wire apron of the paper machine.

In Fig. 4 I illustrate a modification in which a stationary air box 27 is located within a hollow perforated roll 28 and is provided with cut-off partitions 29 and perforated outlets 30 communicating with the chamber or space 31 at the lower portion of the roll so that the air blown from the box 27 is discharged through the lower portion only of the roll. I may also provide a pair of press rolls 28' to press the sheet or fabric against the cut-off partitions 29.

In this modification I also carry out the idea of a pair of endless perforated belts or aprons 32 and 33 between which the sheet 1 is carried and supported in its passage around the blow roll 38.

In the modification illustrated in Fig. 5, I show the blow roll 34, corresponding to the blow roll 3 of the preferred form, as having a perforated cover 35, which may be of wire mesh, around the outside of the roll, and when so equipped, the upper apron or conveyer 24 may be dispensed with as the paper will thus be supported between perforated thicknesses in its passage around the periphery of the blow roll.

The operation is, therefore, as follows: The moist paper coming from across the suction boxes 2 passes over roller 21 and thence between the perforated aprons or belts 24 and 20 and is carried by these aprons and belts around the lower portion of the blow roll 3.

As above stated, the lower chambers of the revolving blow roll are maintained in open communication with the supply from the pipe 17' and valve 9, so that the air which is heated or dried in any approved manner is directed through the lower chambers 15 of the blow roll and through the perforations 18 thereof into contact or through the sheet 1 to carry with it the moisture of the sheet.

This air may be heated to any desired temperature and is under the desired pressure so that the absorption of the moisture is accomplished by the carrying of the water as such along with the air as the latter rushes

through the sheet. If the sheet is not porous, then the air will cause a pressure on the sheet between the two perforated conveyers and the moisture of some of the water will be squeezed out by the pressure.

My improved machine is adapted for use in any type of paper machine or fabric drying machines, and as above stated, the air may be used as a conveyer for chemicals for disinfecting or liquids for coloring the sheet during the blowing operation.

With my improved mechanism lumps or thick spots in the sheet are dewatered or dried as well as the smoother portions of the sheet, and I am enabled to employ any pressure and temperature desired which is not possible with the ordinary suction methods in general use.

Furthermore, my improved machine permits a large volume of hot dry air to be continuously forced through the sheet of paper or fabric under a controllable pressure and volume and it is therefore a continuous process.

It will thus be noted that I utilize a means for holding the sheet smoothly and under pressure and in firm contact with the periphery of the blow roll so that the pressure of the air as well as its temperature is utilized to remove the moisture from the paper and the paper is prevented from being damaged by the pressure because it is supported between the perforated belts, aprons or conveyers. In other words the perforated apron 20 exerts a mechanical pressure on the paper and thereby coöperates with the dry air under pressure in removing the moisture from the paper.

Various other slight changes might be made in the general form and arrangement of parts described without departing from the invention, and hence I do not limit myself to the precise details set forth, but consider myself at liberty to make such changes and alterations as fairly fall within the spirit and scope of the appended claims.

I claim:

1. A paper making machine, comprising a blower having a perforated cover about which the paper to be dried is trained, a pair of perforated supports between which the paper is carried past the perforations of the blower, and means directing dry air radially from said blower through said paper and perforated supports.

2. A paper making machine, comprising a blower about which paper to be dried is trained, means for directing hot air under pressure outwardly through said blower and said paper, and means for holding a sheet against the blower and coöperating with the air in removing the moisture from the paper.

3. A paper making machine, comprising a rotary perforated blower, and a pair of

- endless perforated aprons adapted to support between them a paper sheet and hold the same against the blower, said perforated blower being provided with means supplying air under pressure to said paper. 5
4. A paper making machine, comprising a perforated blower roll, means for directing air under pressure into and through the periphery of said roll, and an endless perforated apron adapted to support a sheet against the blower roll and to coöperate with the air under pressure in removing the moisture from the paper. 10
5. A paper making machine, comprising a blower roll, having partitions dividing the same into compartments, means for directing air into certain of said compartments during the rotary motion of the roll, said roll having peripheral perforations with tapering or enlarged outlets adapted for supplying air to the paper trained about the roll, and means for holding a sheet against the periphery of said roll. 15
6. A paper making machine, comprising a blower roll, partitions in the roll dividing the same into compartments, means for directing air into the lower of said compartments during the rotary motion of the roll, said roll having peripheral perforations with enlarged outlets adapted for supplying air to the paper trained about the blower roll, and a pair of endless perforated aprons adapted to support a sheet against a portion of said roll. 20
7. A paper making machine, comprising a blower, and a pair of perforated paper supports trained about the blower and adapted to hold a sheet of moist paper in contact with the air discharged by the blower. 25
8. A paper making machine comprising a blower having a perforated rim about which paper to be dried is trained, and means for directing dry air through said perforated rim into contact with said paper, 45 the dry air also forming a vehicle for a paper feeding agent. 50
9. A paper making machine comprising a blower having a perforated rim about which paper to be dried is trained, means for directing dry air through said perforated rim into contact with said paper, the dry air also forming a vehicle for a paper feeding agent, and means firmly pressing said paper into engagement with said rim 55 and coöperating with said dry air in removing the moisture from the paper. 60
10. A paper making machine comprising a rotatable blower having a perforated rim and radial partitions defining compartments, an apron trained about said rim and pressing a sheet of paper flatly into contact with a portion of the rim, and means to supply air under pressure to the compartments adjacent the paper whereby air is forced into contact with the paper to coöperate with said apron in removing the moisture therefrom. 65
11. A paper making machine comprising a rotatable blower having a perforated rim and radial partitions defining compartments, an apron trained about said rim and pressing a sheet of paper flatly into contact with a portion of the rim, means to supply air under pressure to the compartments adjacent the paper whereby air is forced into contact with the paper to coöperate with said apron in removing the moisture therefrom, and a reticulated body between the paper and said rim. 70 75

LESTER ERNEST MILKEY.
